UNITED STATES PATENT OFFICE.

CASPER F. SEARCH, OF WINONA, MINNESOTA, ASSIGNOR TO THE WINONA HARVESTER WORKS, OF SAME PLACE.

HARVESTER.

SPECIFICATION forming part of Letters Patent No. 393,397, dated November 27, 1888.

Application filed September 20, 1887. Serial No. 250,157. (No model.)

To all whom it may concern:

Be it known that I, CASPER F. SEARCH, a citizen of the United States, residing at Winona, in the county of Winona and State of Minnesota, have invented a new and useful Improvement in Harvesters, of which the following is a specification.

My invention relates particularly to an improvement in that portion of the mechanism of a self-binding harvesting-machine, wherein means are provided for straightening the grain in delivering it to form the gavel by accelerating the motion of the butt-ends of the grain or retarding that of the heads, or both.

15 The object of my invention is to provide improved means for the purpose, of simple construction and thoroughly effective in operation.

20 My invention consists in the construction of the butt-accelerating mechanism.

My invention also consists in providing spring-arms underneath the shield, extending toward the deck below the shield, to retard the head-ends of the grain; and it further consists in details of construction and combinations of parts, as hereinafter more fully set forth.

25 In the drawings, Figure 1 is a broken longitudinal sectional end elevation of so much of a self-binding harvester as will serve to illustrate my improvement, with which it is provided; Fig. 2, a broken view in elevation of the opposite end of the machine from that shown in Fig. 1; Fig. 3, an enlarged view in outer 30 side elevation of the deck surmounted by the shield, shown broken away to display the spring-retarding fingers provided upon it and the butt-accelerating device; Fig. 4, an enlarged view showing the frame or housing and the parts carried thereby; and Fig. 5, a section taken on the line 5 5 of Fig. 4, viewed in the direction of the arrows, and showing parts in elevation.

40 A is the upper roller of the top apron of the elevator, and B the upper roller of the lower apron, both being automatically and simultaneously adjustable in slots r and q at one end and r' and q' at the opposite end by means of bars p , forming apron-guides, which slots and levers, however, form no part of my present application,

but of another application of mine, Serial No. 250,189, filed simultaneously with the present, and wherein their function and manner of operation are clearly set forth.

Through a slot, a , in the forward side of the frame of the machine below the upper end of the deck C, a short rotary shaft, n , is inserted, carrying at its outer end a sprocket-wheel, D, driven from a similar wheel, D', on the end of the roller B by a chain connection, m . The shaft n is supported at its inner end in a strap, n' , extending downward from the under side of the deck and carrying a stationary cog-wheel, l , centrally through which the shaft n also extends.

65 E is a frame or housing open on one side, as shown, and comprising a central or body portion, x , having four arms, x' , x^2 , x^3 , and x^4 , extending at right angles to each other from the central portion, at which it surrounds and is secured to the shaft n . Around the central portion, x , of the housing or frame E are cog-wheels 1, 2, 3, and 4, supported to rotate on axes, one at the base of each arm x' , x^2 , x^3 , and x^4 , where they surround the central stationary 70 cog-wheel, with which they correspond in size, and are also in mesh with the latter. Near the outer ends of the arms of the housing E are rotary cog-wheels k , k' , k^2 , and k^3 , (the first named being obscured from view in Fig. 1 by the bearing n' ,) all of one size and corresponding with the cog-wheels 1, 2, 3, and 4, with which they are respectively in mesh, and the cog-wheels k , k' , k^2 , and k^3 carry each a finger, 75 F, rigidly secured to its inner face, or forming 80 part thereof, as shown. The deck C is slotted, as shown at i , Fig. 3, in line with the fingers F at the part where the elevator discharges the butt-ends of the grain, and the slot is covered by a correspondingly-slotted convex 85 shield, G, to cause the grain to pass readily over the slot.

H is the shield supported over the deck C on a rod, h , in a bearing, h' , extending from the breast-plate I of the knotter mechanism 90 and adjustable in the slots r^2 r^3 , like the deck C, with the rollers and platform, as and for the purpose set forth in my aforesaid concurrent application. On the under side of the shield H are light easily-flexible spring-fingers 100

K, adjustable in holes *g*, provided in the shield H to receive them, being secured by bolts *f*, nuts *f'*, and washers *f''*, which securing means also renders them readily removable; and the 5 spring-fingers are bent, as shown in Fig. 1, and extend near the surface of the deck C.

Several holes *g* may be provided in line with each other, as shown, to permit transportation of the spring-fingers, and other means 10 than those shown and described may be employed as the releasable securing means of the spring-fingers. I do not, therefore, wish to be understood as limiting myself to the employment of any number of holes *g*, nor to the particular finger-securing mechanism. 15

The operation of my improvement is as follows: The connection of the sprocket-wheels D and D' causes the housing or frame E to be rotated by the rotation of the apron-roller B 20 about the central stationary cog-wheel, *l*, which rotates the fingers F by the gearing connecting them with the center stationary cog-wheel. The fingers are originally set to extend in parallel planes in the same direction, and, as will 25 be seen from the nature of the mechanism, each finger while it makes a complete revolution with that of the frame or housing E is parallel in each position assumed by it to itself in a preceding position. Thus as each finger 30 enters in turn the upper end of the slot *i* it extends to its full limit at or near the center of the slot, and after reaching its limit of extension in leaving the slot at the lower end of the latter it recedes with a species of waving 35 motion, whereby it forces the butt-ends of the grain downward upon the slanting deck without binding it, as it would were its motion imparted directly from the center to cause it to rotate with the shaft *n*. While the fingers 40 F, in extending through the slot *i*, accelerate the butt-ends of the grain for the usual purpose, the spring-fingers K retard the grain toward the head ends, and thus cause it to be delivered in proper position to form the gavel. 45 The rotating-finger device may, however, be employed without the retarding fingers, and vice versa, though I prefer in my particular machine to use them together for the sake of their co-operation. 50

The term "frame" or "housing" herein employed is intended to be sufficiently generic to include any suitable rotatory support for the cog-wheel gear.

What I claim as new, and desire to secure 55 by Letters Patent, is—

1. In a self-binding harvesting-machine, the combination, with the butt-end of the deck, of a shielded slot, *i*, a rotary shaft, *n*, a stationary cog-wheel, *l*, a frame or housing, E, secured to the shaft *n* to revolve with it, cog-wheels 1, 2, 3, and 4, supported to rotate on the frame or housing around the stationary cog-wheel and in mesh with the latter, rotary cog-wheels *k*, *k'*, *k''*, and *k'''*, supported on the frame or housing and respectively in mesh 60 with the cog-wheels 1, 2, 3, and 4, and fingers F on the cog-wheels *k*, *k'*, *k''*, and *k'''*, rotated by the revolution of the frame or housing and maintained by the intermeshing cog-wheel gear parallel to each other and at a uniform 70 angle to the plane of the deck throughout their rotation, and thereby extended consecutively through the slot in the shield G to accelerate the butt-ends of the grain, substantially as described. 75

2. In combination with the butt-end of the deck of a self-binding harvester provided with a slot, the device for advancing the butt-ends of the grain, comprising a revolving frame or housing, E, carrying-fingers which extend 80 through the slot consecutively as the frame or housing revolves, and a system of intermeshing cog-wheels, substantially as shown, rotating the said fingers in a direction contrary to that of the frame or housing, whereby the fingers are always maintained parallel to each other and at a uniform angle to the plane of the deck, a shield, H, supported over the deck, and spring-fingers K, secured to and extending from the shield toward the deck to retard 85 the head ends of the grain, substantially as described. 90

3. In a self binding harvester, the combination, with the deck and shield supported to overhang the deck, of spring-fingers K, secured to and extending from the shield toward the deck to retard the head ends of the grain, substantially as described. 95

4. In a self-binding harvester, the combination, with the deck and shield, the latter having openings *g*, of spring-fingers K, removably secured in the said openings and extending from the shield toward the deck to retard the head ends of the grain, substantially as described. 100
